GERHARDT SIGVERT REHLING KAMPMANN, OF TAULOV-STATION, DENMARK,
ASSIGNOR TO NAAMLOOZE VENNOOTSCHAP HANDEL-MAATSCHAPPIJ "PLA-
NEET," OF THE HAGUE, NETHERLANDS, A CORPORATION OF THE NETHER-
LANDS.

LOCK.

1,401,910.

Specification of Letters Patent. Patented Dec. 27, 1921.

Application filed February 25, 1921. Serial No. 447,749.

To all whom it may concern:

Be it known that I, GERHARDT SIGVERT REHLING KAMPMANN, a subject of the King of Denmark, residing at Taulov-Station, Denmark, have invented certain new and useful Improvements in Locks, for which I have filed an application in Holland, January 12th, 1920, of which the following is a specification.

10 My present invention relates to a lock which when being closed by any one of a series of different keys belonging to the lock is adjusted in such a way that after being closed it can only be opened by the same key.

15 For this purpose I may provide the lock with two sets of plates or flat levers co-operating in pairs in such a manner that each plate in a pair can rotate about a fixed pin, one of the mating plates being provided with a pin and the other with a slot into which said pin projects, the said slot being so formed that when one plate is moved in the one direction, the mating plate 20 moves in the opposite sense so that the sum of the distances from the axis of rotation of the key to those points of the two plates which are nearest to said axis is either constant in all pairs of plates or variable in 25 such a manner that the same variation of this sum in one pair of plates also occurs in all other pairs when the same key is used, in other words, that this sum in all pairs of plates is the same variable amount, 30 preferably so that the relation between the distance from one of the plates of a pair of plates to the axis of the key and the corresponding distance from the other plate of said pair of plates to the said axis may 35 be represented by a simple mathematical formula.

40 When the lock is closed, the first set of plates is adjusted by the turning key in such manner that this set in its turn moves a lever to release the bolt. During its further movement the key moves the bolt into locking position after which a spring moves the lever back into the position in which it locks the bolt, whereby also the first set 45 of plates resumes its initial position. When the rotary movement of the key is still further continued, the second set of plates is adjusted. This set remains in its adjusted 50 position, and its plates are so formed that

their adjustment cannot be affected by the key when turned in the opposite direction.

Any key of the series of keys belonging to the lock has a number of teeth which exceeds the number of plates in the second set by one. This last tooth has the same length in all keys of the series and serves to actuate the bolt, the other teeth being arranged in pairs in such a manner that in a given pair in the series of keys the sum of the lengths of the teeth measured from the axis of the key is either constant and equal to the aforesaid constant for the sets of plates, or variable in accordance with the same formula that applies to the plates.

When after the lock has been closed, the same key is inserted and turned in the direction for opening the lock, it will simply move past the plates of the second set, as these are still adjusted to suit this particular key, whereupon it engages and moves the first set 75 of plates so as to move the lever backward far enough to release the bolt, and finally it moves the bolt back into opening position, after which the lever is returned by the spring into its initial position, thereby locking the bolt and forcing the plates of the first set back into their original positions.

If, however, after the lock has been closed by one key, another key of the series is inserted into the key hole and turned, then, as 85 of each pair of teeth of this key one is evidently longer and one is shorter than those of the first key, one tooth of each pair of teeth will be too long to move past the second set of plates, so that this key cannot be 90 used for opening the lock.

If a key is used which does not belong to the series and which is adapted to move past the second set of plates, then all teeth of this key are obviously shorter than the corresponding teeth of the first key, i. e. in each pair the sum of the lengths of the teeth is smaller than the corresponding sum in the keys belonging to the series. When, therefore, this key is turned until it reaches the 100 first set of plates, the latter are adjusted for a smaller constant or variable than the one it was made for. In that case the lever will not move far enough to release the bolt, and the key will consequently be unable to move 105 the bolt into opening position.

The lock may be made for use on boxes, drawers, cupboards, etc., or as a padlock.

All locks of a particular type may be identical, and keys and locks may be sold separately. Buying a new lock, therefore, does not necessitate the buying of a new key, and vice versa.

Other advantages of the new lock are:

1st. For the opening and the closing of all locks in a house only one key is required; this saves the time and the trouble of looking up the right key whenever a lock is to be opened.

2nd. When for some reason it is desirable to distinguish certain locks in a house from the other locks, all that is required is closing them with another key.

3rd. In case of doubt as to whether an unreliable person is in possession of a key adapted to open the locks, all that is necessary is closing all locks by another key of the set. No new locks are required.

4th. Simplification in the manufacture, as it is no longer required to fit the key(s) for each lock separately.

The accompanying drawing illustrates a drawer lock in accordance with the invention wherein the aforesaid sum of distances and lengths respectively is constant.

Figure 1 is a front view of the lock with the front plate of the lock casing removed.

Fig. 2 is a vertical section along line A—B in Fig. 1.

Figs. 3 and 4 are a front view and a side view respectively of the bolt.

Figs. 5 and 6 are similar views of filler plate 9.

Figs. 7, 8 and 9 are views of plates 11, 13 and 15.

Figs. 10 and 11 are views of plates 18 and 20.

Fig. 12 is a view of the key with which the lock shown in Fig. 1 has been adjusted.

Fig. 13 is a diagram of the lengths of the teeth in case the sum of the distances above referred to is constant.

Fig. 14 is a diagram of the lengths of the teeth in case the relation between the lengths of the teeth of a pair of teeth may be expressed by a linear formula.

The bolt 1 (Figs. 3 and 4) is actuated by the extreme tooth 22^a (Fig. 12) of the key. For the lock shown in the drawing, the keys must have four other teeth 22^b, 22^c, 22^d, 22^e in addition to the said extreme tooth. However, the lock may be constructed for any number of pairs of teeth in addition to the extreme tooth for actuating the bolt.

Bolt 1 has a slot 2 through which projects a pin 3 on the rear plate *a* of the casing for limiting its movements, and an opening 4 which serves to lock the bolt in projected or in withdrawn position with the aid of plate 11, which is the plate indicated by "lever" in the preamble of this specification.

Also secured to the rear plate *a* are pins 5, 6, 7 and 8.

The lever 11 (Fig. 7), which is rotatable about pin 6, faces bolt 1 and has its left hand edge at a distance from the key hole axis which exceeds the distance between said axis and the left hand edge face of the bolt along which the tooth 22^a of the key glides. Said lever is provided near its top with a laterally projecting pin 12, and its thickness is twice that of plates 13, 15, 18 and 20.

The rear portion of pin 12 engages the one or the other of the recesses 4^a, 4^b of opening 4 in the bolt 1, depending upon whether the bolt is out or in. By means of a spring blade 10 which is secured to pin 5, and which with one end bears against a part *a*¹ of the casing and with the other against lever 11, the latter is pressed to the left so that pin 12 always tends to lock the bolt in its opening or closing position.

Facing lever 11 is a second plate 13 (Fig. 8) which is rotatable about the front portion of pin 12 and provided itself with a laterally projecting pin 14. Facing plate 13 is a third plate 15 (Fig. 9) which is rotatable about the fixed pin 6 and which has a slot 16 for receiving pin 14 of plate 13.

The location of the pins and the form of slot 16 are so that if any out of the series of keys is turned in a counter-clockwise direction, plates 13 and 15 are adjusted in such a manner that they move lever 11 through a sufficient distance to the right to allow bolt 1 to freely move, after which the extreme tooth, which has the same length in all keys of the series, projects the bolt by engagement with a recess 1^a of bolt 1. A projection 17 of the bolt 1 thereby comes close enough to the key hole to prevent a key placed in the key hole after the bolt has been projected from being turned in a counterclockwise direction.

When the key is turned a little farther, the spring 10 again presses lever 11 to the left and plates 13 and 15 are returned into their original positions.

Should the key now be turned in a clockwise direction, it would adjust plates 13 and 15 in the same manner as before whereby lever 11 would move to the right against the action of the spring 10, and the bolt 1 would first be released and subsequently retracted. Apparently, therefore, if no other provision were made, any other key of the series would be adapted to open the lock as well, for they all would move lever 11 far enough to the right to release the bolt 1.

In order now that the lock may only be opened by the particular key by which it has previously been closed, a second set of plates is provided at the left hand side of the key hole, said second set being adjusted, when the lock is being closed, in the same manner as the first set, after which, however, it remains in its adjusted position.

A plate 18 (Fig. 10) which is rotatable about fixed pin 7 and provided with a pin 130

19, faces filler plate 9 (Figs. 5 and 6). The filler plate 9 is mounted on pin 7 and is adapted by its own resiliency to be forced a little off the rear plate *a* of the casing, see 5 Fig. 2. Facing plate 18 is a second plate 20 (Fig. 11), which is rotatable about fixed pin 8 and provided with a slot 21 into which projects pin 19 of plate 18. Facing plate 20 is a 10 third plate similar to plate 18, and facing this third plate is a fourth plate similar to plate 20, said third and fourth plates being 15 rotatable about the fixed pins 7 and 8 respectively.

The relative positions of pins 7 and 8, of 20 pins 19 and slots 21 are such that the distance from the axis of the key hole to those parts of plates 18 which are nearest to said axis increases by the same amount by which the corresponding distance from plates 20 to the 25 said axis decreases, and vice versa. Therefore, when one of the keys of the series glides along these plates, the two long teeth of the pairs of teeth move two of the plates from the axis of the key hole, whereby the other two plates are moved toward said axis and adjusted to suit the two short teeth, it being understood that, once adjusted, the four plates remain in these positions. If now the 30 same key is inserted into the lock and turned in the opposite direction, its four teeth 22^b . . . 22^a move past and glide along the plates 18 and 20 without affecting the adjustment of these plates so that the lock can be opened.

In any of the other keys of the series, two 35 of the teeth are obviously longer and two are shorter than those of the first key. The short teeth of course could move past the plates of the second set, but the two long teeth cannot as the plates 18 and 20 are so formed 40 that the face along which a tooth of the key glides during the adjustment is immediately followed by a face 18^a; 20^a forming an angle therewith which does not exceed 90° so that a key turning in the direction for opening 45 the lock is positively arrested.

If a key of an arbitrary form is used, but one which, when turned in a clockwise direction, does not engage any of the plates 18, 20, the sum of the lengths of the teeth in a pair 50 is evidently smaller than that in the keys belonging to the series, the result being that such a key, after having freely moved past plates 18 and 20, cannot, when moving the set plates at the right hand side, move lever 55 11 far enough to release the bolt 1. Such a key, therefore, can not open the lock.

It will now be understood that the adjustment of the lock for a given key can only be effected during the closing of the lock 60 with this particular key and that the lock, once adjusted, can only be opened by the same key by which it was previously closed.

In the examples shown in the drawings, the plates of the second set are held in adjustment by friction between front and rear 65

wall of the casing. This friction, however, may not be too great, so that the adjustment could be interfered with by shocks or vibrations. With a view to this possibility filler plate 9 is provided with a flange 9^a at 70 its top, an eccentric disk 9^b being located therein in a recess opening to the rear side. The eccentric disk 9^b is provided with a head 9^c sunk in an opening of the cover plate *b* of the casing, and is adapted to be 75 turned, for instance, by means of the key itself which should then be suitably formed for this purpose, as its head 9^c presents a groove 9^d. When the eccentric disk 9^b is turned filler plate 9 is pressed just a little 80 toward the front plate *c* whereby the plates 18 and 20 are clamped together and involuntary rotation of said plates is prevented. As the head 9^c is not accessible when the drawer is closed the eccentric disk 9^b cannot 85 be moved as long as the lock has not been opened. As a matter of course the eccentric 9^b may have any other suitable location relative to the casing.

A further security against undesired 90 opening of the lock is attained by providing a flange 9^e of the filler plate 9, the said flange protecting the plates 18 between axis of rotation 7 and faces 18^a from being moved by means of a suitable instrument 95 inserted into the key hole. This flange could also be integral with the front or the rear plate of the casing.

In a certain number of locks lever 11 may be arranged in front of plates 13 and 15, instead of at the rear side, which would render it still more difficult to fraudulently make a fitting key.

Fig. 13 shows a diagram from which it will be understood how, when the sum of the 105 aforesaid lengths is constant and equal to the distance 23—26, 29—31 or 24—25, these lengths themselves in the keys of the series may vary so that, for example, in three different keys the length of the one tooth may 110 be equal to 23—27, 29—30 and 24—28 respectively, that of the mating tooth equal to 27—26, 30—31 and 28—25 respectively.

Fig. 14 shows a similar diagram for the case wherein the sum of the lengths referred 115 to varies in accordance with a linear formula. In this figure, 32—36, 38—39 and 33—37 respectively is the length of the one tooth in three different keys, 36—35, 39—40 and 37—34 respectively that of the mating 120 tooth. It is clear that this diagram refers to only one of an unlimited number of embodiments of the invention.

When constructing the lock, the location of the pins and the form of the slots in the 125 plates should be so chosen, that for all pairs of plates the adjustment for any position corresponds to a point of the particular diagram to which the lock is to be made.

The subject matter of this application is 130

designed as an improvement on applicant's copending application, Serial No. 380834, the claims herein being directed to the improvement involved.

5. What I claim is:—

1. A lock including a bolt, a key operated control therefor, means set by the movement of the key following actuation of the bolt whereby to prevent use of any other key, 10 and means adapted to firmly hold the first said means against moving out of set position.

2. A lock including a bolt, a key operated control therefor, means set by the movement 15 of the key following actuation of the bolt

whereby to prevent use of any other key, and means including an eccentric for holding the first said means against moving out of set position.

3. A lock including a bolt, a key operated 20 control therefor, means set by the movement of the key following actuation of the bolt whereby to prevent operation of the bolt by any other key, and a member between the key hole and the said means to protect said 25 means from unauthorized manipulation through the key hole.

In testimony whereof I affix my signature.

GERHARDT SIGVERT REHLING KAMPMANN.
